COUCH BED

Joseph Martin, New York, N. Y., assignor to
 United States Cabinet Bed Co., Brooklyn,
 N. Y., a corporation of New York

Application March 10, 1934, Serial No. 714,904

11 Claims. (Cl. 5—21)

This invention relates to couch beds in general.

Among the objects of the present invention, it is aimed to provide an improved couch bed in which the main bed section may be equipped with a box spring and a separate mattress and an extension bed section with a flat spring and a separate mattress and in which the mattress for the extension bed section may be permanently secured to such extension bed section.

It is still another object of the present invention to provide an improved bed section adapted for use as the extension bed section of a couch bed having a collapsible upper frame in which the lifting arm for the lifting mechanism of the upper frame is provided with a crossbar resting on the upper face of the extension bed section in collapsed position both freely visible to the attendant at all times and also located at a level above the floor within easy reach of the attendant.

It is still another object of the present invention to provide an improved bed section adapted for use as the extension bed section of a couch bed having a fixed lower frame, a liftable upper frame and an improved simplified arrangement of links connecting the upper frame to the lower frame and operable by a lifting arm which is pivotally connected at one end of the upper frame and is therefore visible to the attendant as well as within easy reach of such attendant.

It is still another object of the present invention to provide an improved couch bed in which the main bed section may be equipped with a box spring and a separate mattress and the extension bed section equipped with a flat spring and a separate mattress, the main bed section being preferably immovable and the extension bed section supported on rollers and movable relative to the main bed section not only into double bed formation but also into entirely separate twin bed formation.

It is still another object of the present invention to provide an improved bed section adapted for use as the extension bed section of a couch bed having a collapsible upper frame in which the lifting arm for the lifting mechanism of the upper frame forms part of a framework pivotally mounted at one end of the upper frame to form a head board for the bed section when raised and forming an anchor for the mattress on the extension bed section when collapsed.

These and other features, capabilities and advantages of the invention will appear from the subjoined detail description of one specific em-

bodiment thereof illustrated in the accompanying drawings in which

Figure 1 is a fragmental front elevation of a couch bed made according to the present invention;

Fig. 2 is a section on the line 2—2 of Fig. 1;

Fig. 3 is a fragmental section on the line 3—3 of Fig. 1;

Fig. 4 is a fragmental front elevation of the couch bed with the extension bed section moved into double bed formation and raised alongside of the main bed section;

Fig. 5 is a fragmental section on the line 5—5 of Fig. 4; and

Fig. 6 is a fragmental detail of a portion of the lifting mechanism in collapsed position.

The couch bed consists essentially of a main bed section 1 and an extension bed section 2.

The main bed section preferably has a rear wall member 3, two side wall members 4 and 5 and a box spring 6 connected to one another with the front side of the bed section between the front edges of the side wall members 4 and 5 and the box spring 6 open to form the entrance for the extension bed section 2 which may with facility be housed within said main bed section beneath the box spring 6. The rear wall member 3 and side wall members 4 and 5 preferably are not mounted on rollers but on plain supporting members 7 preferably to cooperate with the floor or other supporting surface to resist movement when the extension bed section 2 is moved into and out of the main bed section 1. On the box spring 6 of the main bed section 1, there is supported the mattress 8 and in single bed formation on the rear end of the mattress 8, there may be mounted on end the pillows 9, 10 and 11.

The extension bed section 2 is preferably composed of a lower frame 12 and an upper frame 13. The lower frame 12 consists essentially of two side bars 14 and 15 composed of angle iron with their horizontal webs extending inwardly from the lower ends of their vertical webs and two end bars 16 and 17 with their horizontal webs extending outwardly from the lower ends of their vertical webs.

The upper frame 13 consists essentially of two side bars 18 and 19 with their horizontal webs extending inwardly from the lower ends of their vertical webs and two end bars 20 and 21 with their horizontal webs extending inwardly from the upper ends of their vertical webs.

The spring elements 22 and 23 forming the flat spring of the upper frame between the horizontally extending webs of the side bars 18 and

19 and end bars 20 and 21 are preferably connected to such horizontally extending webs as shown in Fig. 2. In collapsed or descended position of the upper frame 13, the horizontally extending webs of the end bars 20 and 21 may be disposed above the edges of the vertically extending webs of the end bars 16 and 17 of the lower frame 12 and the vertically extending webs of the end bars 20 and 21 extend down outside 10 of the vertically extending webs of the end bars 16 and 17 as shown more clearly in Fig. 6.

The end bars 16 and 17 are each preferably connected to one of the end bars 20 and 21 by a pair of collapsible flat links consisting essentially 15 of a long link 24 and a short link 25 for the end bars 16 and 20 and of the long link 26 and short link 27 for the end bars 17 and 21. One end of the long link 24 is pivotally connected to the outside of the vertically extending web of the end 20 bar 16 and the other end of such link 24 disposed to the inside of the vertically extending web of the end bar 20, provided with a pin 28 slidably mounted in the slot 29 of the vertically extending web of the bar 20, and the link 25 is 25 preferably pivoted to the outer face of the intermediate portion of the link 24 at one end and to the inner face of the vertically extending web of the end bar 20 at its other end. The long link 26 is similarly connected to the end bars 30 17 and 21 and the short link 27 to the long link 26 and end bar 21. The long links 24 and 26 are preferably parallel to one another and the short links 25 and 27 also parallel to one another.

The side bars 14 and 15 are each preferably 35 connected to one of the side bars 18 and 19 by a set of collapsible flat links consisting of the links 30, 31 and 32 for the side bars 14 and 18 and of the links 33, 34 and 35 for the side bars 15 and 19. The links 30 and 32 are preferably 40 parallel to one another and pivotally connected at their lower ends to the outer face of the vertically extending web of the side bar 14 and extend to the outer face of the vertically extending web of the side bar 18 and are there provided 45 with pins 36 and 37 respectively slidably mounted in the longitudinally extending slots 140 and 141 formed in the vertically extending web of the side bar 18.

The link 31 is preferably pivotally connected 50 to the intermediate outer face of the link 30 at its lower end and pivotally connected to the outer face of the vertically extending web of the side bar 18 at its upper end.

The links 33 and 35, see particularly Fig. 4, 55 are preferably parallel to one another and operatively connected to the side bars 15 and 19 similar to the manner in which the links 30 and 32 are connected to the side bars 14 and 18. The lower ends of the links 33 and 35 are pivotally 60 connected to the outer face of the vertically extending web of the side bar 15 and the upper ends of such links extend to the outer face of the vertically extending web of the side bar 19 and are there provided with the pins 38 and 39 65 slidably mounted in the longitudinally extending slots 40 and 41 formed in the vertically extending web of the side bar 19. The link 34 is pivotally connected to the outer intermediate face of the link 33 at its lower end and at its upper end to the outer face of the vertically extending web of the side bar 19.

The links 30 and 33 are preferably parallel to one another, so are the links 31 and 34, also the links 32 and 35, also the links 24 and 26 and 75 also the links 25 and 27 all in the interest of the

parallel movement of the frame 13 relative to the frame 12 when raised or lowered.

The control device for the raising and lowering of the frame 13 relative to the frame 12 consists essentially of a pair of flat bent levers 42 5 and 43 having the long arm portions 44 and 45 and the short arm portions 46 and 47 respectively. The free ends of the short arm portions 46 and 47 are pivotally connected to the outer faces of the vertically extending webs of the 10 side bars 18 and 19 respectively at a distance from the ends of the side bars 18 and 19 substantially equal to the length of a short arm 46, 47. The long arm portions 44 and 45 are preferably connected to one another by two cross rods 48 and 49 which cooperate with the arm portions 44 and 45 in forming a head board for the extension bed section or a support for a pillow or the like in open bed formation or as an anchor for engaging the upper face of the mattress 50 20 supported on the flat spring of the upper frame 13 in collapsed or lowered position.

The pins 37 and 39 on the outside of the links 32 and 35 are pivotally connected to the lower ends of the links 51 and 52 respectively. The 25 upper ends of the links 51 and 52 are pivotally connected with the outer faces of the bent levers 42 and 43 respectively at the junctures between their long and short arm portions. The pins 37 and 39 are further pivotally connected 30 to the ends of the links 53 and 54 respectively extending along the inner faces of the vertically extending web portions of the side bars 18 and 19. The other ends of the links 53 and 54 are 35 pivotally connected to the pins 36 and 38 respectively. The links 53 and 54 are preferably parallel as shown.

From the foregoing, it will be seen that the actuation of the long arm portions 44 and 45 toward the upper face of the mattress 50 will 40 cause the upper frame 13 to descend into the position shown in Figs. 1, 2, 3 and 6 and that the actuation of such arm portions 44 and 45 away from the upper face of the mattress 50 into erect 45 position will cause the upper frame 13 to rise into position shown in Figs. 4 and 5.

To facilitate actuation of the upper frame 13 into raised position and furthermore to anchor the same in its uppermost position, the springs 54 and 55 are provided, the spring 54 being connected at one end to the pin 56 extending inwardly from the intermediate portion of the link 32 and at its other end to the upper end of the extension 57 secured to and extending upwardly from the inner face of the vertically 55 extending web of the end bar 17 and the spring 55 being connected at one end to the pin 58 extending inwardly from the intermediate portion of the link 35 and at its other end to the upper end of the extension 59 also secured to and extending upwardly from the inner face of the vertically extending web of the end bar 17.

In the interest of simplifying the construction, the projections 57 and 59 are formed as the upward extensions of the roller brackets 60 and 65 61 respectively of the casters 62 and 63 respectively. The side bar 16 of the lower frame 12 is also provided with casters, to wit the casters 64 and 65 journaled in the brackets 66 and 67 respectively connected to the inner face of the 70 upwardly extending web of the side bar 16.

To form limiting stops for the bent levers 42 and 43 in their erect position, the ends of the end bar 21 preferably extend beyond the side bars 18 and 19 to form an abutment for the 75

lower faces of the short arm portions 46 and 47 as shown in Fig. 4.

To form limiting stops for the extension bed section 2 when normally moved into double bed formation, the end bars 16 and 17 are provided with plates 68 and 69 having the downwardly extending lips 70 and 71 respectively to engage the inwardly extending projections 72 and 73 formed on the lower ends of the front edges of the side wall members 4 and 5.

To form a neat closure for the opening between the front edges of the side wall members 4 and 5 and box spring 6 when the extension bed section 2 is disposed within the chamber formed beneath the box spring 6 of the main bed section 1, the closure board 74 is provided secured to the front faces of the upwardly extending arms 75 of the supporting brackets 76.

It is obvious that various changes and modifications may be made to the details of construction without departing from the general spirit of the invention as set forth in the appended claims.

I claim:

1. In a bed, the combination with a lower rectangular frame, of an upper rectangular frame, bed spring elements associated with said upper frame to constitute a flat bed spring, three pairs of flat links connecting all four sides of said upper frame to said lower frame, the one of said pairs of links connecting the ends of said upper frame to said lower frame having vertically extending parallel faces, being parallel in extent and positioned to move in parallel relation to one another and the other two of said pairs of links connecting the sides of said upper frame to said lower frame having vertically extending parallel faces, being parallel in extent and positioned to move in parallel relation to one another, each of said links being pivotally connected to the lower frame and slot and pin connected to the upper frame, and a lifting control device comprising two parallel levers pivotally connected at their lower ends to said upper frame, cross rods connecting the upper portions of said levers to one another, secondary links connecting the intermediate portions of said levers to the upper ends of one of said pairs of flat links which is connected to the sides of said upper and lower frames to raise or lower said upper frame in a vertical direction insured by the parallel movement of said links, said cross rods serving as a handle to the user and as a pillow support for the bed when said upper frame has been raised.

2. The combination with a lower frame, of an upper frame, two pairs of parallel moving lifting links, each link of one pair pivotally connected to one side of said lower frame and slot and pin connected to one side of said upper frame and each link of said other pair pivotally connected to the other side of said lower frame and slot and pin connected to the other side of said upper frame, a control bracket having levers pivotally connected at their lower ends to said upper frame, cross rods connecting parallel arms of said levers to one another to form a handle for the user and a pillow support when in raised position, and secondary links pivotally connecting the upper ends of said lifting links to intermediate portions of said levers.

3. The combination with a lower frame, of an upper frame, two pairs of parallel moving lifting links, each link of one pair pivotally connected to one side of said lower frame and slot and pin

connected to one side of said upper frame and each link of said other pair pivotally connected to the other side of said lower frame and slot and pin connected to the other side of said upper frame, a control bracket having parallel levers pivotally connected at their lower ends to said upper frame, cross rods connecting parallel arms of said levers to one another forming a handle for the user and a pillow support when in raised position, secondary links pivotally connecting the upper ends of said lifting links to intermediate portions of said levers, and guide links pivotally connecting the ends of the upper frame to the ends of the lower frame to guide said upper frame in a vertical movement when actuated by said lifting links.

4. The combination with a lower frame, of an upper frame, two pairs of parallel moving lifting links, each link of one pair pivotally connected to one side of said lower frame and slot and pin connected to one side of said upper frame and each link of said other pair pivotally connected to the other side of said lower frame and slot and pin connected to the other side of said upper frame, a control bracket pivotally connected at its lower end to said upper frame, secondary links pivotally connecting the upper ends of said lifting links to said control bracket, abutments extending up from said lower frame above the pivotal axis of said lifting links, and springs connecting the upper ends of said abutments to certain of said lifting links to facilitate actuation of the same into raised position.

5. The combination with a lower frame, of an upper frame, two pairs of lifting links, each link of one pair pivotally connected to one side of said lower frame and slot and pin connected to one side of said upper frame, each link of the other pair pivotally connected to the other side of said lower frame and slot and pin connected to the other side of said upper frame, a pair of short links pivotally connected to said upper frame and each of said short links pivotally connected to one link of one of said pairs of lifting links, a pair of parallel levers pivotally connected at one of their ends to said upper frame, connecting links pivotally connecting the upper ends of said lifting links to intermediate portions of said parallel levers, and cross rods connecting parallel arms of said levers to one another to form a handle when raising or lowering said upper frame, and to form a pillow support when raised.

6. The combination with a lower frame, of an upper frame, two pairs of lifting links, each link of one pair pivotally connected to one side of said lower frame and slot and pin connected to one side of said upper frame, each link of the other pair pivotally connected to the other side of said lower frame and slot and pin connected to the other side of said upper frame, a pair of short links pivotally connected to said upper frame and each of said short links pivotally connected to one link of one of said pairs of lifting links, a pair of parallel bent levers pivotally connected at one of their ends to said upper frame, connecting links pivotally connecting the upper ends of said lifting links to the bent portions of said bent levers, and cross rods connecting parallel arms of said levers to one another to form a handle when raising or lowering said upper frame, and to form a pillow support when raised.

7. The combination with a lower frame, of an upper frame, two pairs of lifting links, each link of one pair pivotally connected to one side of said lower frame and slot and pin connected to one side of said upper frame, each link of the other pair pivotally connected to the other side of said lower frame and slot and pin connected to the other side of said upper frame, a pair of short links pivotally connected to said upper frame and each of said short links pivotally connected to one link of one of said pairs of lifting links, a pair of parallel bent levers pivotally connected at one of their ends to said upper frame, connecting links pivotally connecting the upper ends of said lifting links to the bent portions of said bent levers, and cross rods connecting parallel arms of said levers to one another to form a handle when raising or lowering said upper frame, and to form a pillow support when raised.

- side of said upper frame, each link of the other pair pivotally connected to the other side of said lower frame and slot and pin connected to the other side of said upper frame, a pair of short links pivotally connected to said upper frame and each of said short links pivotally connected to one link of one of said pairs of lifting links, a pair of parallel bent levers pivotally connected at one of their ends to said upper frame, connecting links pivotally connecting the upper ends of said lifting links to the bent portions of said bent levers, cross rods connecting parallel arms of said levers to one another to form a lever when raising or lowering said upper frame and to form a pillow support when raised and guide links operatively connecting the ends of said upper frame to the ends of said lower frame to guide said upper frame in a vertical direction when actuated by said lifting links.
8. The combination with a lower frame, of an upper frame, two pairs of lifting links, each link of one pair pivotally connected to one side of said lower frame and slot and pin connected to one side of said upper frame, each link of the other pair pivotally connected to the other side of said lower frame and slot and pin connected to the other side of said upper frame, a pair of short links pivotally connected to said upper frame and each of said short links pivotally connected to one link of one of said pairs of lifting links, a pair of parallel bent levers pivotally connected at one of their ends to said upper frame, connecting links pivotally connecting the upper ends of said lifting links to the bent portions of said bent levers, cross rods connecting parallel arms of said levers to one another to form a lever when raising or lowering said upper frame and to form a pillow support when raised, abutments extending from said lower frame up above the pivotal axis of said lifting links, and springs connecting said lifting links to the upper ends of said abutments to facilitate actuation of said lifting links during frame lifting and frame lowering movement.
9. The combination with a rigid rectangular lower frame, of a rigid rectangular upper frame, three pairs of main parallel links pivotally connected to the lower frame, there being three pairs of horizontally extending slots in said upper frame, a pin secured to the upper end of each of said links and each slidably mounted in one of said slots, one of said pairs of links being movable in planes that are perpendicular to the planes of movement of said other two pairs of links and connecting the ends of said frames, one link of each of said other two pairs of links connecting one pair of sides of said frames, a short link movably connecting the intermediate portion of each of the main links constituting said first mentioned pair of links and one main link of each of said other two pairs of main links with said upper frame, and a control bracket comprising a pair of parallel levers, each lever pivotally connected at its lower end to one side of said upper frame removed from the adjacent end of said upper frame, a secondary link movably connecting the intermediate portion of each lever to the upper end of the adjacent main link connected to an adjacent side of the frame, and cross pieces connecting the portions of said levers beyond said secondary links to form a handle when operating said control bracket, and a pillow support for the upper frame when raised, and an anchor for said mattress when said bracket is lowered.
10. The combination with a rigid rectangular lower frame, of a rigid rectangular upper frame, three pairs of main parallel links pivotally connected to the lower frame, there being three pairs of horizontally extending slots in said upper frame, a pin secured to the upper end of each of said links and each slidably mounted in one of said slots, one of said pairs of links being movable in planes that are perpendicular to the planes of movement of said other two pairs of links and connecting the ends of said frames, one link of each of said other two pairs of links connecting one pair of sides of said frames, a short link movably connecting the intermediate portion of each of the main links constituting said first mentioned pair of links and one main link of each of said other two pairs of main links with said upper frame, a flat bed spring connected to and extending across said upper frame, a removable mattress on said flat spring, and a control bracket comprising a pair of parallel levers, each lever pivotally connected at its lower end to one side of said upper frame removed from the adjacent end of said upper frame, a secondary link movably connecting the intermediate portion of each lever to the upper end of the adjacent main link connected to an adjacent side of the frame, and cross pieces connecting the portions of said levers beyond said secondary links to form a handle when operating said control bracket, a pillow support for the upper frame when raised, and an anchor for said mattress when said bracket is lowered.
11. The combination with a lower frame, of an upper frame having a mattress supported thereon, lifting links connecting said upper frame to said lower frame and including two parallel links, each of said parallel links being slot and pin connected to one side of said upper frame in an area spaced from the end of said upper frame, and a control bracket comprising a pair of parallel bent levers, each bent lever pivotally connected at the free end of its short arm to one side of said upper frame at a distance spaced from the adjacent end of said upper frame substantially equal to the length of its short arm, and secondary links movably connecting the intermediate bent portion of each lever to the upper end of one of said parallel links, and crosspieces connecting said long arms to form a handle when operating said control bracket and a pillow support for the upper frame when raised, the angle of said bent levers relative to said secondary links and their connections enabling the portion beyond said bent portions of said levers to extend substantially parallel to, and spaced from, said upper frame when said upper frame is depressed to engage the upper face of, and to anchor, the mattress on said upper frame and inclined outwardly away from the vertical and inclined upwardly away from the adjacent end of the upper frame when said upper frame is raised when said short arms and said secondary links align with one another and with said upper frame to lock the same against accidental displacement.
